UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR ATTACHING FLAP-SECURING MEANS TO ENVELOPS.

1,265,135.

Specification of Letters Patent. Patented May 7, 1918.

Application filed September 2, 1916. Serial No. 118,217.

To all whom it may concern:

Be it known that I, WILLARD E. SWIFT, a citizen of the United States, residing at Worcester, in the county of Worcester and 5 Commonwealth of Massachusetts, have invented a new and useful Improvement in Machines for Attaching Flap-Securing Means to Envelops, of which the following, together with the accompanying drawings, 10 is a specification.

The invention relates to machines used in the manufacture of that class of merchandise envelopes in which the seal flap and the body of the envelop are provided with circular washers or disks, attached thereto by eyelets; to one of these disks a cord or string is attached, with its free end adapted to be wound successively around the two eyelets and beneath the disks, thereby 15 surely uniting the seal flap and body of the envelop.

The invention consists in providing in a single machine instrumentalities for punching out the washers or disks successively 20 from a continuous strip of material, and for attaching each such washer by means of an eyelet to the seal flap or the body of the envelop, whichever is presented to the attaching mechanism by the operator. The 25 invention further consists in the construction and arrangement of parts whereby these results are accomplished, as hereinafter described with reference to the accompanying drawings, in which—

30 Figure 1 is a front view of the machine.
Fig. 2 is a view in side elevation.

Fig. 3 is a plan view.

Fig. 4 is a fragmentary plan view, on an enlarged scale, certain parts being removed to disclose the construction of other parts.

Fig. 5 is a vertical sectional view, on an enlarged scale, of the washer forming mechanism.

Fig. 6 is a perspective view, showing the construction of a washer conveying member, and

Fig. 7 is a view representing a merchandise envelop having a washer attached 50 thereto.

Similar reference characters refer to similar parts in the different figures.

In said drawings 1 represents the framework of the machine, which supports the

various operative parts hereinafter described and provides bearing for a driving shaft 2. The shaft 2 is belt driven by a pulley 3, through a one-revolution clutch, not shown, of any desired construction. Inasmuch as this clutch forms no part of the present invention, no description thereof is deemed necessary; it being sufficient to say that it may be operated, at desired intervals, through a treadle or other device commonly employed in machines of this class, to cause the parts to go through a single cycle of operations, each time an envelop, Fig. 7, is presented in position to have a washer secured thereto.

The form of machine herein shown contemplates the punching out of washers from a continuous strip of material, and to this end the frame 1 carries on one side a bracket 4 in which a reel or spool 5 carrying a roll of washer material in strip form, such as heavy paper, is journaled. The strip material 6 feeds downwardly from the reel, and is carried horizontally across the front of the machine, passing into the bight of feed rolls 7, 7 which are journaled in brackets 8, 8, the latter projecting outwardly from the frame 1 on the opposite side of the machine from the reel 5. To insure against an undue strain by the feeding of the material, a guide wheel 9, which is employed to change the direction of feed, is carried by one arm of a bell crank 10 which is pivoted at 11 to the frame. The other arm of the bell crank has attached thereto a spring 12 which operates to yieldingly press the wheel 9 against the strip; this serves in the usual way to take up any slack in the strip and also permits, during feeding, a movement of the wheel 9 in response to strain on the material, thereby avoiding breakage.

The lower feed roll 7 is journaled in brackets 8, 8; the upper feed roll 7 is journaled in blocks 13, 13 which are movable vertically in said brackets, said blocks being under the pressure of a spring 14 acting through the bar 15. The force of spring 14 is variable by means of an adjusting screw 16 to adapt the feed rolls to material of varying thickness, and to press the material between said rolls with sufficient force to prevent any slipping thereof during feeding. The upper roll 7 is driven by a shaft 17 and the two rolls are geared together.

in rotation in unison by means of gears 18, 18. The other end of shaft 17, at the rear of the machine, carries a ratchet 19, and a pawl 20 carried by an arm 21 loosely journalized on the shaft cooperates with the ratchet 19 to impart rotative movement to the shaft when said arm 21 is rocked. The free end of arm 21 has an elongated slot 22 which receives a pin 23 carried on the 10 end of a vertically reciprocating rod 24.

The rod 24 is reciprocated once for each rotation of the shaft 2 by means of a cam 25 on said shaft, coöperating with a fork 26 on said rod, whereby, through the mechanism above described, the feed rolls 7 are rotated through a predetermined arc to advance the strip material the requisite distance for a single washer to be punched from the body thereof.

20 The feed roll brackets, heretofore referred to, are preferably carried by a block 27 which forms part of the washer punching mechanism of the machine. This block 27 supports a die-holder 28, preferably made 25 in two parts in order to afford access to a circular apertured die 29 carried by the lower half of the holder. The two parts of the die-holder afford a horizontal slit or passageway 30 therebetween, through 30 which the washer material is drawn by the intermittent action of the feed rolls 7, 7, as above described. Preferably a plate 31 is attached to that side of the die-holder on which the strip of material enters the slit 30, said plate providing a slot 32 somewhat narrower than the slit 30 and more closely conforming to the width of the washer strip or tape, in order to keep the latter in proper alignment. The opening through the die 29 40 corresponds in size to the washer which is to be punched out from the tape 6 at each cycle of operations of the machine, said tape being somewhat wider than the diameter of this washer in order to preserve its continuity for the action of the feed rolls 7, 7 thereon, after the washers are punched.

Coöperating with the die 29 is a punch 33 which is attached to the lower end of a reciprocating sleeve 34 movable in a bearing 50 35 of the frame. Within the sleeve 34 and bearing against an interior shoulder 36 thereof is a stiff spring 37, the other end of which bears against a flange 38 which is capable of sliding inside the sleeve. A 55 threaded cap 40 closes the end of this sleeve and an operating rod 41 passes loosely through this cap. The flange 38 is attached to rod 41 by means of a rod 42, whose upper reduced end, passing through the disk, 60 is threaded into the lower end of rod 41.

As shown in Fig. 2, the rod 41 is pivotally connected at 43 with a lever 44 which is pivoted at 45 to the framework. At each cycle of operations of the machine the lever 44 is 65 rocked or vibrated once in each direction,

by means of a rod 46 which carries a fork 47 for coöperation with a cam 48 on the main shaft 2.

As a consequence of this operation, the rod 41, starting downwardly from the position shown in Fig. 5, effects initially the descent of the sleeve 34 and punch 33, the spring 37 being of sufficient stiffness to cause these parts, in the absence of resistance, to move in unison. The punch 33, coöperating with the die 29, forms a circular disk which is carried downwardly through the die and against a stationary set 49 supported by the block 27. The movement of the punch 33 being thus arrested, the further descent of operating rod 41 presses the flange 38 downwardly within the sleeve 34 to compress spring 37 and thereby to move the rod 42 independently of sleeve 34. Rod 42 has projecting therefrom a punch 50 85 slideable in the punch 33 but normally, as shown in Fig. 5, terminating just short of the end of the latter. The independent descent of rod 42, as above described, after the disk of material has been punched out and 90 pushed through the die 29, causes the punch 50 to operate, in conjunction with the central aperture 51 of the set 49, to punch a hole in the disk and thereby to complete the washer which is to be subsequently attached to the envelop.

In the space which receives the upper end of set 49 is adapted to slide a horizontal washer carrier 52. The latter is shown, in detail, in Fig. 6 and consists of an arm 53 in 100 the form of a segment of a circle, the same being attached to a sleeve 54 which is adapted to vibrate about the vertical axis provided by a pivot screw 55 carried by the framework. The under side of arm 53 has 105 a groove 56 therein which receives the portion of set 49 projecting above the block 27, so that said set forms no obstruction to the movement of said arm. When the operation of punching out a washer from the tape 6 is 110 in progress, as above described, the arm 53 is stationary, and in such position that the set 49 registers with an aperture 57 at one end of groove 56. This aperture 57 provides a shoulder 58, above which it is of the same 115 diameter as the washer, the distance of this shoulder from the top surface of the arm 53 being approximately the thickness of the washer material. Below the shoulder 58 the aperture 57 corresponds in size to the set 49, 120 so that as the disk or washer is deposited by the descent of punch 33, it rests near its periphery upon the shoulder 58 and inwardly thereof upon the set 49. In this position it is punched out by the punch 50, as described 125 above.

A web 59 projecting from sleeve 54 has an upstanding lug 60 thereon which is pivotally connected to a bar 61 extending toward the rear of the machine, as shown in Figs. 2 and 130

4. At its rear end the bar 61 is pivoted to one arm of a bell crank 62, which is adapted to be rocked about an axis 63 by means of a cam 64 on the shaft 2, which coöperates with a cam roll 65 carried by the other arm of the bell crank. After the washer has been formed by the punches 33 and 50, as above described, the action of cam 64 is inaugurated to swing the segmental arm 53 into the position shown in Fig. 4, the groove 56 riding over the set 49, from which the punch 50 has been withdrawn by the return of the sleeve 34 to the position shown in Fig. 5. The washer, disposed within the aperture 57 and resting on the narrow shoulder 58, is carried by arm 53 to a position to be operated upon by the eyelet setting mechanism of the machine, as hereinafter described.

It is to be understood that this eyelet setting mechanism, which attaches the washer, by means of an eyelet, to the flap or body portion of the envelop Fig. 7, may be of any well known type, such, for instance, as that described in Letters Patent No. 1,131,805, issued to me March 16, 1915, or in the pending parent application Serial No. 777,998, of which the application for the above Letters Patent constitute a division. Or, if desired, the eyelet setting mechanism may be of the form illustrated and described in Letters Patent No. 923,602, issued to me June 1, 1909, and covering a machine which, simultaneously with the attachment of a washer to the flap of the envelop, Fig. 7, secures a closing cord 88 thereto by the same operation which sets the eyelet used to attach said washer. For purposes of illustration, I have shown an eyelet chute 66 of the type described in the aforesaid Letters Patent No. 1,131,805, with its lower end in position to hold an eyelet beneath a spring pressed eyelet needle 67 adapted to remove the lowermost eyelet from the chute 66 as the set 68 descends, the needle being arranged to engage the eyelet frictionally and prevent its falling off after the lower end of the chute has been pushed out of the way. The eyelet set 68 is carried by a vertically reciprocating plunger 69, moving in vertical ways 70 provided by the framework. The plunger is supported from a fixed pivot 71 by means of a toggle-joint composed of links 72 and 73, said joint being actuated by a rod 74 pivotally attached at its forward end to the knee 55 of the toggle joint and at its rear end to one arm 75 of a bell crank which is pivoted at 76 to the frame. Another arm 77 of the bell crank is pivotally connected at its end to an actuating rod 78, which is driven from an offset portion of crank 79 of the shaft 2.

As is usual in mechanism of this nature, the actuating rod 78 includes a yieldable portion 80 to prevent injury to the machine in the event that the complete descent of the set 68 is prevented by a broken or deformed eye-

let, or by any other unforeseen circumstances.

With the flap 84 or body portion 85 of the envelop, Fig. 7, in proper disposition with respect to the usual lower needle 81 of the eyelet setting mechanism, (see Fig. 4) the descent of the set 68, carries the eyelet 86 into the central aperture of the washer 87, as held in position by the swinging arm 53. The washer 87 is flexed or pushed through the aperture 57 of the arm by this movement, being strung in effect upon the neck portion of the eyelet 86. The washer being thus removed from the arm 53, the latter is free to return to a position where it may receive another washer when the cycle of operations is repeated, and its return is permitted because the aperture 57 is opened, as at 82, for movement past the set 68. The continuing descent of set 68 effects, 85 in conjunction with the anvil 81, the flanging of the eyelet to securely affix the washer to the envelop, as well known in the art to which this particular portion of the mechanism pertains.

It is to be understood that the present invention contemplates the employment, in conjunction therewith, if desired, of mechanism for applying a reinforcing tab on the other side of the envelop wall from the washer, as set forth in the aforesaid Letters Patent No. 1,131,805; to this end an operating connection 83 may be included for actuating the feeding devices for the tape from which the tabs are made, but since this feeding mechanism forms no part of the present invention, it is deemed unnecessary to disclose the same. In such a case the lower needle 81 would be made shorter than herein shown, and would constitute in connection with the set a means for punching through the body of the envelop.

It is also to be understood that the present invention contemplates the attachment of a washer simultaneously with the affixing of a closing cord thereto, as set forth and described in the aforesaid Letters Patent No. 923,602. In such a case the connection 83 would serve for the operation of the string feeding means, not herein shown, since the same constitute no part of the present invention. Under such circumstances, the lower needle 81 would be constructed substantially as shown, being made hollow and open on one side for the passage of the string, and as described in said Letters Patent No. 923,602, would coöperate with the set 68 in severing the string as well as in setting the eyelet used to attach the string and washer to the flap of the envelop.

I claim:

1. In a machine of the class described, the combination with eyelet-setting mechanism for affixing a washer to an article, of mechanism for successively forming and sepa-

rating washers from a continuous strip of washer material, and means for conveying each washer from the forming mechanism to the eyelet-setting mechanism.

5. 2. In a machine of the class described, the combination with eyelet-setting mechanism for affixing a washer to an article, of means for feeding a strip of washer material by successive steps, mechanism for forming a 10 separate washer therefrom at each step, and means for conveying each washer from the forming mechanism to the eyelet-setting mechanism.

15. 3. In a machine of the class described, the combination with eyelet-setting mechanism for affixing a washer to an article, of means for conveying washers to said eyelet-setting mechanism, means for feeding a strip of washer material, and means for punching a 20 disk washer from said strip, said last named means being operable to dispose the disk in position for movement by said conveying means.

25. 4. In a machine of the class described, the combination with eyelet-setting mechanism for affixing a washer to an article, of means for conveying washers to said eyelet-setting mechanism, means for feeding a strip of washer material, and means for forming a 30 washer from said strip and disposing the same in position for movement by said conveying means.

35. 5. In a machine of the class described, the combination with eyelet-setting mechanism for affixing a washer to an article, of means for conveying washers to said eyelet-setting mechanism, means for feeding a strip of washer material and means for punching a 40 disk from said strip and disposing it in position for movement by said conveying means, said punching means including means for perforating said disk, while in such position, to form a washer.

45. 6. In a machine of the class described, the combination with means for punching out a disk from a strip of material, of a member adapted to receive the disk, means for perforating the disk, while on said member, to form a washer, and means for thereafter 50 moving said member, to render the washer available for use.

55. 7. In a machine of the class described, the combination with eyelet-setting mechanism adapted to affix a washer to an envelop, of a washer conveying member adapted in one position to hold a washer in position for the action of said eyelet-setting mechanism, and in a second position to have a disk of washer material superposed thereon, 60 and punching mechanism above said member, adapted in the second position of said member to deposit a disk of washer material thereon, said punching mechanism including means for forming a washer from said disk 65 by perforating the same.

8. In a machine of the class described the combination with eyelet setting mechanism adapted to affix a washer to an envelop, of a washer conveying member adapted in one position to hold a washer in position for 70 the action of said eyelet-setting mechanism and in a second position to have a disk of washer material superposed thereon, and punching mechanism above said member, adapted in the second position of said member to deposit a disk of washer material thereon, said punching mechanism including means for forming a washer from said eye 75 before the movement of said member to the above first mentioned position.

9. In a machine of the class described, the combination with eyelet-setting mechanism adapted to affix a washer to an envelop, of a washer conveying member adapted in one position to hold a washer in position for 80 the action of said eyelet-setting mechanism, and in a second position to have a disk of washer material superposed thereon, and punching mechanism above said member, adapted in the second position of said member to deposit a disk of washer material thereon, said punching mechanism including 85 means for forming a washer from said eye before the movement of said member to the above first mentioned position.

90. 10. In a machine of the class described, the combination with eyelet-setting mechanism adapted to affix a washer to an envelop, of a washer conveying member adapted in one position to hold a washer in position for 95 the action of said eyelet-setting mechanism, and in a second position to have a disk of washer material superposed thereon, and punching mechanism above said member, adapted in the second position of said member to deposit a disk of washer material thereon, said punching mechanism including means for forming a washer from said disk 100 while the latter is supported on said member, and before movement of said member from the above second mentioned position.

11. In a machine of the class described, a slidable washer conveying member, means for punching a disk from a strip of washer 115 material and disposing same on said member, said punching means having perforating means for forming said disk in a washer, including a support for the center of said disk, said conveying member having a 120 groove to receive said support in the travel of said member.

12. In a machine of the class described, a slidable washer conveying member, having an aperture therein, and providing a shoulder to support a disk of washer material within said aperture, means for punching a disk from a strip of washer material and disposing same within said aperture, and a support projecting into said aperture to the 130

height of said shoulder, said conveying member having a groove to receive said support in the travel of said member.

13. In a machine of the class described, a
5 slidable washer conveying member, having
an aperture therein, and providing a shoulder to support a disk of washer material
within said aperture, means for punching
a disk from a strip of washer material and
10 disposing same within said aperture, and
means coöoperating with said support to
punch out the center of said disk.

14. In a machine of the class described, a

reciprocating actuating means, disk punching mechanism having a yielding connection therewith, and means for punching out the centers of disks which are formed by said disk punching mechanism, said last named means having a positive connection with said actuating means.

Dated this 25th day of August, 1916.
